IKE ROSENBLUM, OF JERSEY CITY, NEW JERSEY

SLIPPER OR THE LIKE

Application filed September 19, 1931. Serial No. 563,706.

This invention relates to improvements in shoes and has particular reference to a soft sole slipper and means for securing together elements thereof.

5 An object of the invention is to provide an improved slipper of simple and inexpensive construction, the assembly of which will eliminate some of the operations incident to the making of slippers now in common usage.

10 Another object is to connect together various elements constituting a slipper by means of a securing member which is mounted within the sole of the slipper and provided with means which will penetrate said elements and thereby effectively bind the same to each other.

15 The above and other objects will appear more clearly from the following detailed description, when taken in connection with the 20 accompanying drawing, which illustrates a preferred embodiment of the inventive idea.

In the drawing—

Figure 1 is a perspective view of a slipper constructed in accordance with the invention; 25 Figure 2 is a top plan view of the slipper, partly broken away and shown in section;

Figure 3 is an enlarged fragmentary transverse section through the slipper, showing the elements thereof partially assembled; 30

Figure 4 is a similar view of the elements completely assembled and secured together; and

35 Figure 5 is a fragmentary perspective view of the securing member forming a part of the invention.

In the method usually employed in manufacturing soft sole slippers, the outer sole and upper are stitched or otherwise secured together in reversed position. The inner sole or padding and sock lining are secured by a suitable adhesive and the former is then cemented to the surface of the outer sole which ultimately becomes the inner surface when the elements are all assembled and the 40 upper of the slipper and the outer sole are reversed to their positions of usage.

45 The present invention is designed to eliminate the above-described operations in the assembly of the elements of the slipper which, 50 as shown in the drawing, comprise the outer

sole 6, the upper 7, the inner sole or padding 8 and the sock lining 9, all made of any suitable material. In assembling these elements it is not necessary to reverse the positions of the outer sole and upper, as in the customary method, due to the use of the securing member generally indicated by the numeral 10 and which includes some of the essential features of the present invention. 55

This member 10 is formed from a single strip of relatively light flexible metal which is shaped generally to conform to the contour of the sole of the slipper. The strip is formed to provide continuous flanges 11 at the end portions thereof, which flanges are 60 adapted, when the member is in position in the slipper, to extend along the instep portion thereof. For this purpose, the flanges are curved upwardly, as indicated in Figure 5, and, in order to increase the rigidity of the flanges and thereby form an adequate support for the instep, each flange is provided with a longitudinal corrugation or rib 12. The extremities 13 of the strip at the outer ends of 65 said flanges are turned inwardly toward each other and are provided with apertures to receive suitable fastening devices 14 which are driven into the heel of the slipper so as to anchor the strip in position. 70

The intermediate portion of the strip, that is between the inner ends of the flanges 11, includes a plurality of spaced lugs 15 disposed in substantially the same plane as the flanges 11. Throughout the entire length of the strip, the same is provided with a series 80 of securing prongs 16 extending upwardly from the flanges 11 and lugs 15 and the sharpened extremities of which are designed to penetrate the various elements of the slipper when binding the same together. 90

By reference to Figures 3 and 4, it will be seen that in assembling the slipper the flanges 11 and lugs 15 are interposed between the outer and inner soles 6 and 8, with the prongs 16 extending along the marginal edge of the inner sole. The marginal edge of the outer sole 6 is then turned upwardly and the extremities of the prongs are caused to penetrate said outer sole, as clearly indicated in 95 Figure 3. The edge of the upper 7 is then 100

- positioned in interposed relation between the extremities of the prongs and the lining 9, after which, by suitable instrumentalities, the prongs 12 are forced downwardly and then outwardly to the position shown in Figure 4, during which movement they will be caused to penetrate the upper 7, lining 9 and finally the inner sole or padding 8. In this position the elements of the slipper will be completely assembled and bound together. The portions of the elements constituting the heel of the slipper may be secured together in the manner which is customarily employed in making slippers of this character.
- 15 16. What is claimed is:
1. In a shoe, inner and outer soles, an upper, and a securing member having a portion interposed between said soles and means penetrating the latter and said upper to secure them together.
  2. In a shoe, a sole, an upper, and a flexible securing member interposed between said sole and upper and extending along the edges thereof, said member having a plurality of penetrating elements for securing the sole and upper together, with the securing member completely hidden from view by the sole and upper.
  3. In a shoe, inner and outer soles, an upper, and a securing member having a plurality of spaced lugs and a continuous flange interposed between said soles, and further having a plurality of bendable prongs penetrating said soles and upper to bind the same together.
  4. In a shoe, inner and outer soles and a shoe upper, and means for securing said soles and upper together to form a shoe, said means including a flexible strip of metal having portions inserted between the soles, and penetrating prongs engaging with both soles and the upper, the flexible strip of metal being hidden from view by the outer sole member.
- 45 In testimony whereof, I have affixed my signature.

IKE ROSENBLUM.
